CLAIM

The ornamental design for mirror kit, as shown and described.

DESCRIPTION

FIG. 1 is a perspective view of the mirror kit in an open position;

FIG. 2 is a front elevational view thereof in an open position; FIG. 3 is a top view thereof in an open position;

FIG. 4 is a right side elevational view thereof in an open position;

FIG. 5 is a bottom view thereof in an open position;

FIG. 6 is a back elevational view thereof in an open position; and,

FIG. 7 is a perspective view thereof in a closed position.

The broken lines are shown for illustrative purposes only and form no part of the claimed design.
